Clock Case Front

No. 3437

PATENTED
MAR 30 1869

John D. Pepple

Inventor
John D. Pepple

George M. Pepple

Applicant.

ELIAS INGRAHAM, OF BRISTOL, CONNECTICUT.

Design No. 3,437, dated March 30, 1869.

DESIGN FOR THE FRONT OF A CLOCK-CASE.

The Schedule referred to in these Letters Patent and making part of the same.

To all whom it may concern:

Be it known that I, ELIAS INGRAHAM, of Bristol, county of Hartford, and State of Connecticut, have invented or produced a new and original Design for a Clock-Case Front; and to enable others skilled in the art to make the same, I will proceed to describe it, reference being had to the letters marked thereon, which indicate like parts.

In the accompanying photographic view is shown a new and original design for a clock-case front.

a are straight, square-edge sides.

b is straight, square-edge, oblique, or double-slant top of the case.

c is a bead-configuration, upon the oblique or double-

slant edge of the top, and the upper portion of the sides.

d are beaded column-configurations upon the edge of the sides *a*.

The whole is combined to produce a plain, ornamental design for a clock-case front.

What I claim, and desire to secure by Letters Patent, is—

The design for a clock-case front, as above described and set forth.

ELIAS INGRAHAM.
